MINE RAIL TIE AND RAIL SECURING
DEVICEJames Morano and Sam Morano, Morgantown,
W. Va.

Application February 3, 1939, Serial No. 254,471

1 Claim. (Cl. 238—60)

This invention relates to certain new and useful improvements in mine rail tie and rail securing devices.

The primary object of the invention is to provide a mine rail tie constructed of heavy gauge sheet metal having a central longitudinally extending knee pressed rib with the side edges of the tie bent downwardly and inwardly upon themselves to provide a longitudinally extending rib at the bottom of each side edge of the tie in the plane of the knee pressed central rib for reinforcing the tie and providing ground anchor means.

A further object of the invention is to provide a mine rail tie and rail securing device of the foregoing character wherein the securing means for each rail includes a rail engaging clamp rigid with the tie and a pair of rail engaging clamps supported by vertical pivots respectively on ears projecting laterally of each side of the tie with means on the tie for holding each of the pivoted rail engaging clamps in rail engaging position.

With the above and other objects in view that will become apparent as the nature of the invention is better understood, the same consists in the novel form, combination and arrangement of parts hereinafter more fully described, shown in the accompanying drawing and claimed.

30 In the drawing:

Figure 1 is a top plan view of a mine rail tie constructed in accordance with the present invention, a pair of rails being fragmentarily illustrated as supported thereon with the devices for securing the rails in position on the tie, one of the latter devices being illustrated by dotted lines in its rail releasing position;

Figure 2 is a side elevational view of the tie with the rails shown in cross-section;

Figure 3 is a vertical cross-sectional view taken on line 3—3 of Figure 2, showing the pivotally mounted rail engaging clamps supported on ears projecting laterally of the tie;

Figure 4 is a cross-sectional view taken on line 4—4 of Figure 2, showing the longitudinally extending depressed rib and the turned under side edges of the sheet metal tie for reinforcing the tie and providing ground anchor means; and

Figure 5 is a cross sectional view, similar to Figure 4, of another form of tie with the rail omitted.

Referring more in detail to the accompanying drawing, the mine rail tie 5 is constructed of heavy gauge sheet metal and as shown more clearly

ly in Figs. 1, 3 and 4, the upper face of the tie has a central longitudinally extending V-shaped depression or groove 6 therein, defining a depending longitudinally extending tie reinforcing and ground anchor rib 7 of substantially V-shape 5 as illustrated. As shown more clearly in Figures 3 and 4, the longitudinal side edges of the tie 5 are bent downwardly and inwardly to lie beneath the tie in engagement therewith to provide ribs 8 cooperating with the rib 7 for reinforcement of the tie and to facilitate ground anchoring of the tie. Suitable radial cuts are made in the side edges of the tie 5 so that during the bending of such side edges to provide the reinforcing ribs 8, laterally projecting 15 ears 9 are provided for the pivotal support of rail securing devices with the ears 9 lying in the plane of the tie 5.

The tie 5 has rails 10 mounted thereon and the securing devices for each rail include a rail 20 engaging clamp 11 rigid with the tie 5 and engaged with one side of the rail, while a pair of pivotally mounted rail engaging clamps are mounted on the ears 9 for engagement with the other side of the rail. Each pivotally mounted 25 rail engaging clamp arm designated in general by the reference character 12 has a pair of vertically spaced parallel legs 13 and 14 projecting from one side thereof to straddle an ear 9 and be pivotally mounted thereon by the pin or rivet 30 15, the upper leg 13 of the clamp being in a plane above the tie 5 and movable over the upper surface of the tie during adjustment thereof while the lower leg 14 of the pivoted clamp is of a length relative to the length and width 35 of the ear 9 to permit free pivotal movement of the clamp on said ear as shown in Figures 1 to 3. The other side of the rail engaging clamp 12 carries an upwardly directed arm 16 and a horizontally extending foot 17, the arm 16 being 40 engageable with the upper side of the base flange of the rail 10 while the foot 17 is disposed beneath the base rail and in engagement therewith as shown in Figure 2. Each rail engaging clamp arm 12 has a latch rod 18 associated therewith for holding the clamp arm 12 in rail engaging position and as shown in Figure 1, the latch rod 18 is pivoted as at 19 on the upper face of the rail 5 with one end thereof movable into engagement with the side of the upper leg 50 13 of the rail engaging clamp 12.

By locating the pivotal rail engaging clamps on the ears 9 in the plane of the tie 5, the clamps are lowered with respect to the tie so that a minimum of obstructions is offered to 55

coal loading machinery and other equipment travelling on the rails 10. Should the pivotal rail engaging clamps become damaged, replacement thereof is made relatively easy without disturbing the general tie structure. The formation of the longitudinally extending ribs 7 and 8 centrally and at the edges respectively of the tie provides desired reinforcement for the sheet metal tie as well as providing sufficient ground anchor means.

10 The sheet metal tie shown in Figure 5 and designated by the reference character 5a has the side longitudinal edges thereof bent downwardly, inwardly, and then outwardly to provide a side edge reinforcement, foot, or rib 8a of three thicknesses, while the longitudinally extending V-shaped depression 6a centrally of the tie 5a provides the central depending longitudinal rib 7a of the same depth as the side feet 8a for the proper reinforcement of the sheet metal tie. In bending the side edges of the tie to provide the side edge supporting feet of three thicknesses, portions thereof are cut out and remain in the plane of the tie 5a to provide the laterally extending ears 9a for the pivotal mounting of a rail engaging clamp.

15 From the above detailed description of the invention, it is believed that the construction and use thereof will at once be apparent and 20 while there are herein shown and described the preferred embodiments of the invention, it is

nevertheless to be understood that minor changes may be made therein without departing from the spirit and scope of the invention as claimed.

We claim:

15 In a mine rail tie and rail securing device, a sheet metal tie having a central longitudinally extending depending reinforcing rib, the side edges of the tie being turned under and engaged with the bottom face of the tie to form reinforcing ribs with all of said ribs disposed 10 in the same horizontal plane to facilitate ground anchoring of the tie, rail securing devices carried by the tie for each rail thereon comprising a rail engaging clamp rigid with the tie and a pair of rail engaging clamps respectively pivotally mounted at opposite side edges of the tie, the mountings for the pivoted clamps including ears projecting laterally of and in the plane of the tie, each pivotally mounted clamp including an overlying rail flange engaging arm and a 20 lower cooperating rail flange engaging foot, and a pair of superposed spaced legs respectively disposed above and below said mounting ear with the lower side of the lower leg being in the plane of the lower sides of said tie ribs 25 for frictional ground contact to prevent accidental pivotal movement of the clamp relative to the supporting ear and rail flange.
